CONTAINER FOR FLAT ARTICLES

Stephen P. Midouhas, Bristol, Pa., assignor to
Kemline Metal Products Company, Bristol, Pa.,
a corporation of Pennsylvania

Application May 6, 1948, Serial No. 25,325

5 Claims. (Cl. 206—60)

1

This invention relates to flat containers and relates more particularly to novel corner reinforcing means for flat receptacles.

An important object of the invention is to provide a novel container formed of heavy cardboard or other sheet material and designed primarily for the packing and shipping of flat articles. Many conventional flat containers used in shipping somewhat fragile articles are provided with separately fitted corner reinforcing brackets which protect the contents against blows delivered against the edges and also act as spacer elements to protect the contents against undue compressive force when a quantity of the containers are stacked, one upon the other.

An object of the present invention is to provide an improved container of inexpensive construction wherein novel corner reinforcing means are formed integrally with the flat container by providing plural inturned tongues on each side of the several corner sections and which protect the contents against side blows as well as compressive force.

Another object of the invention is to provide an improved flat container having reinforcing means of the character described which can be produced at substantially the same cost as a conventional flat package.

A further object of the invention is to provide a container construction wherein the inturned tongues effectively space the flat contents inwardly from the edges of the closed container and retain the contents in such inwardly spaced position. Thus, any blows which may be delivered to the edges of the container during transit are absorbed by the container itself and do not damage the contents.

In the drawing:

Fig. 1 is a bottom plan view of a flat container embodying the present invention.

Fig. 2 is a top plan view thereof, partly in section.

Fig. 3 is a plan view of the container in open position.

Fig. 4 is a broken side elevation of the closed container.

Fig. 5 is a broken section taken on line 5—5 of Fig. 2.

Fig. 6 is a broken section taken on line 6—6 of Fig. 2.

Fig. 7 is a broken section taken on line 7—7 of Fig. 2.

The container, shown in open position in Fig. 3, including a rectangular lower wall 9 defined by fold lines 10, relatively shallow vertical side 55

2

walls 11, 12, 13 and 14, carried integrally along such fold lines 10 and top wall sections 15, 16, 17 and 18, respectively, formed integrally with the side walls along fold lines 19.

5 In the illustrated container the side walls are relatively shallow and their height will be varied depending upon the thickness of the article carried therein. Opposed top wall sections 17 and 18 are relatively narrow and are first folded inwardly, after which the remaining opposed top wall sections 15 and 16 are folded inwardly and are of such width as to meet along a center line 20. The proportions of such top wall sections may also be varied without departing from the 15 invention.

Along each edge of the container adjacent each corner section a tongue 23 is formed by providing two spaced, generally parallel cuts 24 lying more or less perpendicular to the edge. No material 20 need be removed.

The method of assembling the container is as follows. The blanks may first be cut to shape including cuts 24 and scored along fold lines 10 and 19. They are preferably packed and shipped 25 flat to the place of use. The flat article or articles 26 to be enclosed, shown in broken lines in Figs. 2 and 3 and full lines in Figs. 5, 6 and 7 may first be placed on the lower wall 9 and the narrower top wall sections 17 and 18 then folded 30 inwardly along fold lines 19 and 10. In this folding operation each portion between spaced cuts 24 is pushed inwardly to the position shown to form the tongues 23. The operation is repeated 35 with respect to top wall sections 15 and 16. The container may then be sealed by applying a strip of adhesive tape (not shown) across the center line 20.

By pushing in the tongues, small notches 27 remain along the edges. The tongues retain the 40 flat article in spaced relation to the side walls. In Figs. 5, 6 and 7 the contents 26 of the container are shown as being relatively thick, compared with the thickness of the stock used in forming the container. In most instances where the contents are somewhat thinner, the double layer of material forming the tongues act as the spacer elements when the filled containers are stacked one upon the other.

While one form or embodiment of the invention 50 has been shown and described herein for illustrative purposes, and the construction and arrangement incidental to a specific application thereof have been disclosed and discussed in detail, it is to be understood that the invention is limited neither to the mere details or relative

arrangement of parts, nor to its specific embodiment shown herein, but that extensive deviations from the illustrated form or embodiment of the invention may be made without departing from the principles thereof.

I claim:

1. A container for flat articles formed from a blank of sheet material having a plurality of intersecting lines of fold defining a lower wall, side walls and upper wall sections forming closure flaps, each edge of the container having a pair of spaced cuts lying generally perpendicular with such edge and extending through the side wall and into the top and bottom walls, the material disposed between each pair of cuts being disposed inwardly of such edge to form a tongue which spaces the flat article inwardly of such edge.

2. A container for flat articles formed from a blank of sheet material having a plurality of intersecting lines of fold defining a lower wall, side walls and upper wall sections forming closure flaps, each edge of the container having a plurality of pairs of spaced cuts lying generally perpendicular with such edge and extending through the side wall and into the top and bottom walls, the material disposed between each pair of cuts being disposed inwardly of such edge to form a tongue.

3. A container for flat articles formed from a blank of sheet material having a plurality of intersecting lines of fold defining a lower wall, side walls and upper wall sections, at least two of such opposed upper wall sections meeting substantially at the central median line of the container and forming closure flaps, the remaining upper wall section being of lesser width than the first mentioned upper wall section, each edge of the container having a plurality of pairs of spaced cuts lying generally perpendicular with such edge and extending through the side wall

and into the top and bottom walls, the material disposed between each pair of cuts being disposed inwardly of such edge to form a tongue which forms an abutment to space the article from the edge of the container.

4. A container for flat articles formed from a blank of sheet material and including a lower wall, side walls, and upper wall sections formed integrally with said side walls and forming closure flaps, each side wall of the container having plural spaced cuts adjacent each corner section which extend into the upper and lower walls, the cuts being generally perpendicular with the edge and the material disposed between such cuts lying inwardly of such edge to form abutments which space the contents of the container from the edges thereof, such tongues also forming corner reinforcing elements.

5. A container for flat articles formed from a blank of sheet material having a plurality of intersecting fold lines defining a lower wall, side walls and upper wall sections forming closure flaps, each edge of the container having spaced cuts adjacent each corner section which extend through the side wall and into the upper and lower walls, the cuts being generally perpendicular with such edge and the material disposed between such cuts lying inwardly of such edge to space the contents of the container from the edges thereof, such tongues also forming corner reinforcing elements.
